UNITED STATES PATENT OFFICE.

CHARLES C. COX, OF ARLINGTON, MASSACHUSETTS.

DESIGN FOR A BRACKET.

SPECIFICATION forming part of Design No. 13,169, dated August 8, 1882.

Application filed July 6, 1882. Term of patent 7 years.

To all whom it may concern:

Be it known that I, CHARLES CLARK COX, a citizen of the United States, residing at Arlington, in the county of Middlesex and State of Massachusetts, have invented and produced a new and original Design for a Bracket, of which the following is a specification, reference being had to the accompanying drawing, forming part thereof.

10 This bracket has the usual supporting right-
angular plate, A A.

The design consists of the following elements: first, a right-angular border, B B, consisting of a flat bar of a form corresponding to 15 the base-plate or support A A, this border standing out somewhat from the base-plate and united to it by connecting struts a a, &c.; second, in a flower or other ornament, C, located in the corner of the border B B, and sur-
20 rounded on the two outer sides by a right-an-

gular band, D D, cast integral with the border, and forming a rectangular inclosure to contain said flowers; third, in a scroll or other ornament, E, located in the right-angular spaces b b bounded by the border and band D D, and 25 to be united to the latter by struts c c, &c., the outer portion, d, of each of these ornaments being practically a straight bar, in order that the entire outline of the bracket may be a right-angled triangle. 30

I claim—

The design herein described, and represented in the accompanying fac-simile.

In testimony whereof I affix my signature in presence of two witnesses.

CHARLES CLARK COX.
